UNITED STATES PATENT OFFICE

WILSON E. PORTER, OF NEW HAVEN, CONNECTICUT, ASSIGNOR TO THE NEW HAVEN CLOCK CO., OF NEW HAVEN, CONNECTICUT, A CORPORATION

CENTER FRICTION FOR CLOCKS AND WATCHES

Application filed December 1, 1927. Serial No. 236,959.

My invention relates to an improvement in center-frictions for clocks and watches, the object being to provide, at a low cost for manufacture, simple and reliable means for

5 frictionally coupling the hands of a clock or watch with the driving-train thereof, so as to permit the hands to be turned independently of the train for purposes of setting, whereby the spring friction-washers heretofore employed for frictionally coupling the hands of a clock or watch with the driving-train thereof are dispensed with, and the number of parts in a given time-mechanism reduced.

15 With these ends in view, my invention consists in initially bending the center-arbor of a time-mechanism so as to place its respective ends out of line, so that when straightened out, due to its installation in the concentric 20 passage of a member of the driving-train of a time-mechanism, sufficient friction will be developed between it and the said driving-member to cause the arbor to normally revolve with the said member, but free to be 25 turned in either direction independently thereof.

My invention further consists in a center-friction for clocks and watches, characterized as above, and having certain details of construction as will be hereinafter described and particularly recited in the claims.

In the accompanying drawings:

Fig. 1 is a broken view in central section of a watch-movement embodying my improved center-friction; and

Fig. 2 is a detached view in elevation of a center-arbor forming an element of my improvement.

In carrying out my invention, as herein shown, I employ a center-arbor 5 which is preferably reduced in diameter, as at 6, near its rear end, to better enable its respective ends to be bent slightly out of line. Such an arbor, initially so bent, is driven into the concentric passage 7 of the center-pinion 8 of the time-train of any standard watch or clock with enough force to substantially straighten it out and thus develop sufficient friction between it and the walls of the said passage to frictionally couple them with the coherence

required to cause the arbor to rotate with the pinion under the normal running conditions of the time-train, so that the arbor will be driven thereby.

As shown, the passage 7, in which the center-arbor 5 is installed, is slightly greater in diameter than the diameter of the arbor, so that, while the arbor, as substantially straightened, as described, as an incident of its installation in the said passage, makes sufficient contact with the walls thereof for the development of the friction-coupling required for driving the arbor, it is not bound therein, so that while the arbor will normally be driven by the center-pinion, which, as usual, mounts the center-wheel 9, it will yield for turning independently thereof in either direction to permit the setting of the clock or watch, whether that is effected by manually turning the minute-hand 10 or by turning the same indirectly through the medium of the dial-train, as, for instance, in a watch of the familiar stem-winding and stem-setting type. The minute-hand 10 aforesaid is mounted in the usual manner directly upon the reduced forward end 11 of the arbor, while its companion hour-hand 12 is mounted, as usual, upon a hub or sleeve 13 carried by an hour-wheel 14 mounted upon and freely turning independently of the center-arbor which passes through them. A minute-wheel pinion 15, fixed upon the said arbor, so as to rotate therewith, meshes into a wheel 16 of the dial-train, this wheel carrying a pinion 17 meshing into and driving the hour-wheel 14 aforesaid. As shown, the center-pinion 8 is reduced at its front and rear ends respectively, having bearing in the front and rear movement-plates 18 and 19.

Preferably and as shown, the arbor is provided with the reduced portion 6 to facilitate bending it, though this is not imperative.

It will be clear from the foregoing that under my invention the friction-washers ordinarily employed for frictionally coupling the center-arbors and driving-trains of time-movements are dispensed with and the center-pinion itself caused to discharge their function, whereby the number of parts is reduced and a great saving secured without any loss

of effectiveness. My invention is particularly adapted to small watch-movements where economy of space is of vital importance, and in which the parts are so minute as to make their production, assembly and installation a delicate and expensive operation.

I claim:

1. The combination with a member of the driving-train of a clock or watch, the said member having a concentric passage formed therein, of a cylindrical center-arbor initially bent bodily so as to place its respective ends out of line, whereby, when installed in the said passage, it is sufficiently straightened thereby to develop the friction required for normally yieldingly coupling the said arbor and driving-member with a capacity for the independent turning of the arbor for setting the mechanism.
2. The combination with a member of the driving-train of a clock or watch, the said member having a concentric passage formed therein, of a cylindrical center-arbor formed between its ends with a reduced portion and initially bent bodily at such reduced portion to place its ends out of line, whereby, when installed in the said passage, it is sufficiently straightened thereby to develop the friction required for normally yieldingly coupling the said arbor and driving-member with a capacity for the independent turning of the arbor for setting the mechanism.

In testimony whereof, I have signed this specification.
